JOHN LOCHNER.

UNITED STATES PATENT OFFICE.

JOHN LOCHNER, OF NEW YORK, N. Y., ASSIGNOR TO THE HOPKINS & DICKINSON MANUFACTURING COMPANY, OF SAME PLACE.

DESIGN FOR ORNAMENTATION OF BUILDERS' HARDWARE.

SPECIFICATION forming part of Design No. 13,511, dated January 2, 1883.

Application filed November 9, 1882. Term of patent 7 years.

To all whom it may concern:

Be it known that I, JOHN LOCHNER, a citizen of the United States, residing in the city and State of New York, have invented and produced a new and original design for the ornamentation of locks, hinges, knobs, butts, flush-bolts, mortise, surface, and door bolts, sash-locks, sash-lifts, cupboard-catches, barrel-bolts, square case-bolts, bat and coat hooks, drawer-knobs, escutcheons, roses, and all kinds of door, cupboard, and window trimmings comprised in the term "builders' hardware."

The accompanying photograph of my design represents it as displayed upon each of the plates of a hinge; but it will be understood that the shape and dimensions of the design will be varied to conform to the shape and dimensions of the spaces afforded for its display by the various objects to which it is applied.

The characteristic feature of the design consists in the central rosette, *a*, which is formed in relief, and which is adjoined on two sides by panels or portions of panels, as the case may be, representing basket-work *b*, also formed in relief. The other two sides of the rosette are adjoined by a border, *c*, represent-

ing a braid in relief. This border may extend either wholly or partially around the basket-panels *b*.

I produce my design preferably by casting 30 the object upon which it is to be displayed in molds in which the design is formed in reverse.

The design may be colored by gilding, bronzing, or otherwise, and, if desired, different portions of the design may be of different 35 colors.

I claim—

The herein shown and described design for the ornamentation of the surfaces of locks, hinges, knobs, or other objects comprised in 40 the term "builders' hardware," the same consisting of the central rosette, *a*, adjoined on two sides by the representations of basket-work *b*, and upon the other two sides by the representations of braid *c*, the said rosette, 45 basket-work, and braid being formed in relief, as set forth.

JOHN LOCHNER.
